SOOT BLOWER

Willis P. Thomas, Highland Park, Mich., assignor
to Diamond Power Specialty Corporation, De-
troit, Mich., a corporation of Michigan

Application November 21, 1932, Serial No. 643,762

4 Claims. (Cl. 122—392)

This invention relates to a soot blower or fluid heater cleaner of the type in which a blower element is arranged to discharge cleaning fluid adjacent the parts of a fluid heater or the like to be cleaned.

One of the primary objects of this invention is to provide a soot blower of the above mentioned character which will include means for cooling the blower element to prevent the same from being destroyed by the heat of the fluid heater in which the blower element is mounted.

A further object of this invention is to provide an improved blower unit which will include a passage for the cleaning fluid and one or more additional passages for a cooling fluid, the arrangement being such that the composite element or unit so formed will be maintained relatively cool.

The above and numerous other objects and advantages of this invention will become more apparent as the following description proceeds, particularly when reference is had to the accompanying drawing, wherein:

Fig. 1 is an elevational view partly in section of a soot blower constructed in accordance with the teachings of this invention;

Fig. 2 is a sectional view taken substantially on the line 2—2 of Fig. 1;

Fig. 3 is a sectional view taken substantially on the line 3—3 of Fig. 1;

Fig. 4 is a sectional view taken substantially on the line 4—4 of Fig. 1;

Referring then particularly to the drawing wherein like reference characters designate corresponding parts throughout all views, there is disclosed in Fig. 1 a fluid heater such, for example, as a boiler having a wall or setting 15 and the boiler tubes 16. Mounted in an opening in the setting is a wall box 17 through which a blower element 18 extends. The blower element is provided with suitable discharge nozzles for directing jets of cleaning fluid adjacent parts of the fluid heater to be cleaned, such, for example, as the boiler tubes 16.

Exteriorly of the setting the blower element is journaled in a blower head designated generally by the reference character 20. This blower head comprises a gooseneck 21 in which one end of the blower element is journaled to receive cleaning fluid from the same. Cleaning fluid is supplied to the other end of the gooseneck by a supply pipe 22, there being provided a valve 23 for controlling the flow of cleaning fluid from the supply pipe to the gooseneck. This head may be conveniently supported from the wall box by

a floater 24, in accordance with the usual practice.

For rotating the blower element there is provided a sheave wheel 25 adapted to be driven by a suitable actuating chain. This sheave wheel drives a pinion 26 which in turn drives a gear 27 fixed to the blower element so that rotation of this gear effects a rotation of the blower element.

For actuating the valve 23 in timed relation to the rotation of the blower element, there is provided a cam 28 fixed for rotation with the gear 27. This cam is arranged to engage a suitable lever 29 which in turn is connected to the valve stem 30 of the valve 23. This is of general construction and provides that as the blower element is rotated, the valve 23 is periodically opened and closed so that cleaning fluid is admitted to the blower element during a portion only of its rotative movement.

The blower element being mounted as it is within the boiler or fluid heater, tends to become extremely hot and the present invention contemplates the provision of means for keeping this blower element relatively cool under all conditions. This cooling is effected by causing a cooling fluid to flow longitudinally of the element from the outer to the inner end thereof and then back to the outer end of the blower element where the cooling fluid is discharged into a suitable drain or the like. The construction will find particular utility when installed in relatively wide fluid heaters or the like for the reason that in such heaters it is undesirable for the blower element to extend entirely across the same; thus as illustrated, in Fig. 1 of the drawing, the blower element extends only half way through the fluid heater, there being shown one end of a second blower element 18 which it will be understood extends from the opposite side of the fluid heater or boiler.

To accomplish the desired cooling the blower element is formed of walls 60 suitably secured together along longitudinal lines as by welding or the like to form passages 61, 62 and 63. It will be noted that the passage 61 is substantially oval in section and is disposed centrally of the unit, the passages 62 and 63 being substantially crescent-shaped in section and lying on opposite sides of the passage 61. The passage 61 constitutes a passage for the cleaning fluid, and there are therefore provided nozzles 64 which communicate with the central passage to provide for the discharge of cleaning fluid therefrom adjacent the parts of the boiler to be cleaned. It

will be noted that the several walls are so secured to each other that the nozzles 64 may be placed in communication with the passage 61 by passing through a single wall of the composite element or unit 18.

The passages 62 and 63 constitute passages for the cooling fluid, the passage 63 being the cooling fluid inlet passage or the passage through which the cooling fluid flows from the outer to the inner 10 end of the blower element and the passage 62 being the cooling fluid outlet passage or the passage through which the cooling fluid flows from the inner end of the blower element to the outer end thereof. It will be understood that these 15 passages communicate with each other at the inner or distal end of the blower element, as clearly illustrated at 65 in Fig. 1 of the drawing.

For the purpose of supplying cooling and cleaning fluids to the several passages of the blower 20 unit, the structure shown in Fig. 1 is provided. By reference to this figure it will be noted that the gooseneck is provided with a bearing portion 66 which is chambered to provide an annular chamber 67 which surrounds the blower unit and 25 which communicates with the supply passage in the gooseneck. Formed in the blower element, and communicating with the passage 61 are openings 68, these openings registering with the annular chamber 67 so that cleaning fluid may enter 30 the passage 61 from the gooseneck.

The blower unit is extended beyond the gooseneck and is journaled in a suitable fitting 70. This fitting is provided with an annular chamber 71 into which a fluid discharge pipe 72 is tapped. 35 The blower element is provided with a port 73 which communicates with the passage 62 and registers with the annular chamber 71 so that cooling fluid in passage 62 may be discharged from this passage by way of chamber 71 and 40 pipe 72.

The fitting 70 is also provided with an annular chamber 75 into which a fluid supply pipe 76 is tapped. A port 77 formed in the blower element provides communication between chamber 75 and 45 the passage 63 of the blower element so that cooling fluid supplied to the chamber 75 by way of pipe 76 may enter the blower element.

It is believed that the operation of the invention 50 will be clearly apparent. Whenever the blower element is rotated the valve 23 will be actuated to periodically admit cleaning fluid to the passage 61 of the blower unit. This cleaning fluid may be discharged from this passage by way of nozzles 64 to adjacent the parts of the fluid heater to be 55 cleaned.

At all times, regardless of whether the blower element is discharging cleaning fluid or not, a 60 cooling fluid may flow from supply pipe 76 through chamber 75 and port 77 into the passage 63 of the blower unit. This cooling fluid may flow longitudinally of the blower unit to the distal end thereof and then flow back through the unit by way of passage 62. This cooling fluid will be 65 discharged from the passage 62 by way of port 73, chamber 71 and discharge pipe 72. It will be apparent that the passages for the cooling fluid substantially surrounding as they do the cleaning fluid passage will keep the walls of this latter 70 passage cool and will thus keep the entire unit sufficiently cool to prevent the same from being destroyed by the heat to which it is exposed in the fluid heater. The walls of the blower unit being integrally united as they are, will provide

for the distribution of the heat to the several walls of the unit by conduction, with the result that the flowing of the cooling fluid through the cooling fluid passages will maintain the element cool.

From the above it will be apparent that the 5 invention provides a soot blower which includes a blower element which may be permanently mounted in a fluid heater or the like and which will be so cooled as not to be destroyed by the heat to which it is exposed. As illustrated, the 10 blower element preferably comprises a composite unit which provides not only a cleaning fluid passage but also passages for a cooling fluid, the latter passages providing that a cooling fluid may flow in reverse directions longitudinally of the 15 blower element.

While the invention has been described with some detail, it is to be understood that the description is for the purposes of illustration only and is not definitive of the limits of the inventive 20 idea. The right is reserved to make such changes in the details of construction and arrangement of parts as will fall within the purview of the attached claims.

What I claim as my invention is:

1. In a soot blower, in combination, a steam pipe, a water conduit in thermal communication with said steam pipe, said conduit extending serially along one side of said pipe and back along another side of said pipe outside of said pipe, a 30 bearing for said pipe and conduit, and means for rotating said pipe within said bearing, said steam pipe being provided with means for discharging steam onto adjacent parts to be cleaned of soot.

2. In combination, in a soot blower, a pipe having perforations in a wall thereof, a water conduit thermally connected to said pipe, said conduit extending serially along one side of said pipe and back along another side of said pipe outside of said pipe, bearing means for said pipe and conduit, said bearing means providing a steam space surrounding said pipe and conduit, said pipe having a port communicating with said steam space, said bearing means also providing a pair of spaced water spaces surrounding said pipe and conduit, 45 said conduit having a pair of ports communicating with said pair of water spaces for permitting circulation of water through said conduit and means for turning said pipe and conduit within said bearing means.

3. In a soot blower, in combination, a pipe having perforations therein, water conduit means, said conduit means extending serially along one side of said pipe and back along another side of said pipe outside of said pipe, and bearing means 55 for said pipe and conduit means, said bearing means being provided with port means for admitting steam to the interior of said pipe, said bearing means being also provided with ports for admitting water to and discharging water from 60 said conduit means.

4. In a soot blower, in combination, a pipe having perforations in its wall and water conduit means thermally connected to said pipe, said conduit means extending serially along one side of 65 said pipe and back along another side of said pipe outside of said pipe, a bearing for said pipe and conduit means, said pipe and conduit means being provided with a cylindrical portion cooperating with said bearing, and means for communicating a turning movement to said pipe and conduit means.

WILLIS P. THOMAS.
